UNITED STATES PATENT OFFICE.

MARSHALL ROME BOLES AND ARTHUR JOSEPH SNAVELY, OF FOUNTAIN CITY,
TENNESSEE.

COIL BOX.

Application filed March 9, 1925. Serial No. 14,274.

To all whom it may concern:

Be it known that we, MARSHALL R. BOLES and ARTHUR JOSEPH SNAVELY, citizens of the United States, residing at Fountain City, 5 in the county of Knox and State of Tennessee, have invented new and useful Improvements in Coil Boxes, of which the following is a specification.

This invention relates to improvements in 10 internal combustion engines, the general object of the invention being to provide means whereby the coils of the ignition system of the engine are located above the engine so that the coils will be kept dry from the heat 15 of the engine and from the circulating air from the fan and the coils can be wired to the various parts with less wire.

Another object of the invention is to provide means for holding the coils against 20 movement in the supporting means and to provide means for making the coils readily accessible.

This invention also consists in certain 25 other features of construction and in the combination and arrangement of the several parts, to be hereinafter fully described, illustrated in the accompanying drawings and specifically pointed out in the appended claims.

30 In describing the invention in detail, reference will be had to the accompanying drawings wherein like characters denote like or corresponding parts throughout the several views, and in which:—

35 Figure 1 is a partial view of a motor showing our invention in use.

Figure 2 is a view of the coil supporting device with the cover thereof removed to show the coils in position.

40 Figure 3 is an end view.

Figure 4 is a section on line 4—4 of Figure 2.

Figure 5 is a section on line 5—5 of Figure 3.

45 Figure 6 is a section on line 6—6 of Figure 5.

Figure 7 is a perspective view of one of the terminal members.

50 Figure 8 is a partial sectional view of such member showing the same connected with the post and with the wire.

Figure 9 is a fragmentary view of one of the coils.

In these views, 1 indicates a casing which

has the U-shaped legs 2 fastened to its body, 55 these legs being adapted to be fastened to the head of a motor A by means of some of the bolts a which fasten the head to the block. Thus the casing is supported above the head. One side of the casing is left open 60 and this side is adapted to be closed by a hinged cover 3 which is hinged to a strip 4 connected to the brackets 5 which are also adapted to be fastened to the head by some of the bolts a. The ends of the casing 1 are 65 provided with extensions 1', the outer and top edges of which are adapted to be engaged by the cover 3 when the same is in closed position. These extensions 1' are so formed that spaces 6 are left at the ends of 70 the casing, when the cover 3 is in closed position, so that the air from the fan of the motor can circulate through the device and come in contact with the coils supported 75 therein to keep the same free from moisture.

The amount of air passing through the device can be regulated through means of the slide 7 at the front end of the casing which is adjustably held in position by means of the nuts and bolts 8, the bolts passing 80 through slots 9 in the slide. The cover is held in closed position by the latch 10. The casing is divided into four chambers by the partitions 11, each chamber receiving a coil B and the coils are held in the 85 chambers by the turn buttons 12 pivoted to the outer edges of the partition. Blocks 13 are fastened to the upper portions of the partitions for engaging the upper ends of the coils for holding the coils against movement in the chambers. A strip 14 of metal is placed in a longitudinal groove 15 formed in the bottom of the casing and this strip is connected with the binding post 16 which receives a conductor leading from the switch of the ignition system. Spring contacts 17 are fastened to this strip and these contacts are adapted to engage the contacts b placed on the bottom of the coils, each member 17 having a beveled 90 part 17' so that the contact will be depressed as the coil is slid into the chamber and thus automatically engage the contact b. A hole 18 is formed in the front of the casing through which the wires 19 for connecting the terminals b' of the coils to the timer pass. The conductors 20 lead from the terminals b'' of the coils to the spark plugs, these wires pass-

ing over the outer edge of the bottom of the casing through the space between said edge and the cover 3 to the spark plug.

A lamp socket 21 is carried by the rear 5 end of the casing for receiving a small lamp which can be used to illuminate the interior of the device so that the parts therein can be easily seen at night or on dark days. The conductor wires for this lamp are shown 10 at 22.

We prefer to use a terminal clip, such as shown at 23, in Figures 7 and 8, for connecting the wire to the terminal, this clip being formed of spring metal with a loop 15 24 at one end to receive a bent part 25 at the other end, the parts of the loop and the part 25 being provided with holes to receive the terminal post, as shown in Figure 8. The tendency of the limbs of the clip will 20 hold the edges of the holes in firm engagement with the post. The conductor wire is adapted to be soldered or otherwise fastened to the top of the clip.

From the foregoing it will be seen that 25 we have provided a casing for the coils which is fastened to the top of the engine and is so formed that the coils and their conductors will be subjected to the heat from the engine and to the air from the 30 fan. Thus the coils and the wires will be kept free of moisture and but a small amount of wire is necessary to make the connections. It also eliminates the use of porcelain or other insulators, such as are 35 used where the wires pass through the dash board. Broken circuits or the like are more readily found and are more easily remedied in this arrangement than in the old style arrangement of placing the coils on the dash. 40 The parts can be easily examined and by throwing the cover 3 down it will act as a support for tools and the like. By firmly fastening the coils in the chambers all movement of the coils is prevented so that the 45 contacts are in firm engagement at all times. The lamp permits the parts to be illuminated at night.

It is thought from the foregoing description that the advantages and novel features 50 of the invention will be readily apparent.

We desire it to be understood that we may make changes in the construction and in the combination and arrangement of the

several parts, provided that such changes fall within the scope of the appended claims. 55

What we claim is:

1. In an internal combustion engine, a coil box, means for fastening the same to the top of the engine so that coils in the box will be subjected to the heat from the engine and 60 the ends of the box having openings therein through which the air from the fan will pass.

2. In an internal combustion motor, a coil casing, partitions therein dividing the 65 same into coil receiving chambers, means for detachably holding the coils in the chambers, legs connected with the bottom of the casing and adapted to be attached to the top of the engine by the top bolts and a hinged 70 cover connected with a part of the engine top and arranged to cover one side of the casing.

3. In an internal combustion motor, a casing having one side open, extensions at 75 the ends extending beyond the open side, partitions dividing the casing into coil receiving chambers, means for detachably holding the coils in the chambers, means for preventing movement of the coils in 80 the chambers, legs connected with the bottom of the casing and adapted to be fastened to the engine top by the bolts of said top, a strip adapted to be bolted to the engine top, a cover hinged to said strip for closing the 85 open side of the casing, said cover engaging the end extensions, a slide vertically adjustable on the front end of the casing for controlling the passage of air under the casing and into the space formed by the 90 cover and the extensions.

4. In an internal combustion motor, a coil casing, means for fastening the same to an engine top, means for holding coils in the casing, a hinged part for the casing, a lamp 95 for illuminating the casing, a contact strip in the bottom of the casing, spring contacts thereon for engaging the bottom contacts of the coils, electric connections for the lamp and coils and means for controlling the 100 passage of air from the fan through the casing.

In testimony whereof we affix our signatures.

MARSHALL ROMEO BOLES.
ARTHUR JOSEPH SNAVELY.
